Primary Examiner — Messina L Smith*Assistant Examiner* — Kaitlyn G Wiltshire(74) *Attorney, Agent, or Firm* — BakerHostetler(57) **CLAIM**

The ornamental design for a melter, as shown and described.

DESCRIPTION

FIG. 1 is a front right side perspective view of the melter, showing the new design;

FIG. 2 is top view thereof;

FIG. 3 is a right side view thereof;

FIG. 4 is a left side elevation view thereof;

FIG. 5 is a bottom view thereof;

FIG. 6 is a backside view thereof; and,

FIG. 7 is a front side view thereof.

The broken lines in the figures depict portions of the melter that form no part of the claimed design.
